CLAIM

What is claimed is an ornamental design for a mini-flood light, as shown and described.

DESCRIPTION

FIG. 1 is a perspective view of a mini-flood light showing the top, the front, and the left side;

FIG. 2 is a front elevational view of the mini-flood light of FIG. 1;

FIG. 3 is a rear elevational view of the mini-flood light of FIG. 1;

FIG. 4 is a right side elevational view of the mini-flood light of FIG. 1;

FIG. 5 is a left side elevational view of the mini-flood light of FIG. 1;

FIG. 6 is a top plan view of the mini-flood light of FIG. 1; and,

FIG. 7 is a bottom plan view of the mini-flood light of FIG. 1.

In the drawings, the broken (phantom) lines depict unclaimed subject matter only and form no part of the claimed design.
